US0D1110265S

(12) **United States Design Patent** (10) **Patent No.:** **US D1,110,265 S**
(45) **Date of Patent:** **** Jan. 27, 2026**

(54) **IMPELLER**

(71) Applicant: **SainStore Technology Co., Ltd.,**
Guangdong (CN)

(72) Inventors: **Hua Liao**, Guangdong (CN); **Ting Xiang**, Guangdong (CN)

(**) Term: **15 Years**

(21) Appl. No.: **29/941,439**

(22) Filed: **May 9, 2024**

(51) **LOC (15) Cl.** **13-03**

(52) **U.S. Cl.**

USPC **D13/115**

(57) **CLAIM**

The ornamental design for an impeller, as shown and described.

DESCRIPTION

FIG. 1 is a perspective view of an impeller showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a rear perspective view thereof.

1 Claim, 8 Drawing Sheets
